CURTAIN ROD

Jacob Goldstein, Bronxville, and Hall Y. Kaighin, New York, N. Y., assignors to Kirsch Company, Sturgis, Mich., a corporation of Michigan

Application December 13, 1956, Serial No. 44,178

Term of patent 14 years

(Cl. D21—1)

Fig. 1.

Fig. 2.

Fig. 3.

Fig. 4.

Fig. 1 is a front perspective view of a curtain rod embodying our new design;

Fig. 2 is a top plan view thereof;

Fig. 3 is a front elevational view; and

Fig. 4 is a side elevational view thereof.

The dotted lines are intended to indicate indeterminate or indefinite length.

We claim:

The ornamental design for a curtain rod, substantially as shown and described.
